(57) **CLAIM**

The ornamental design for a cabinet for turntable, as shown and described.

DESCRIPTION

FIG. 1 is a front elevational view of a turntable cabinet showing my new design;

FIG. 2 is a left side elevational view thereof, the right side view being a mirror image;

FIG. 3 is a top, left and front perspective view thereof; and, FIG. 4 is a rear elevational view thereof.

The broken lines showing in FIGS. 1-4 are for illustrative purposes only and form no part of the claimed design.
